UNITED STATES PATENT OFFICE.

ADOLF MOELLER, OF EBERSWALDE, NEAR BERLIN, GERMANY, ASSIGNOR TO O. MUS-TAD & SON, OF OSLO, NORWAY.

MANUFACTURE OF HORSESHOE NAILS.

Application filed May 15, 1928, Serial No. 277,864, and in Germany January 2, 1926.

This invention relates to the manufacture of horseshoe nails by a cold process and more especially to a process in which nails are formed from a continuous wire by a pressing operation, the press being of the type generally called four die press. The usual way to work such presses for this purpose is to feed the wire only about half way into the press, so that the shank of the nail will, after the pressing, be formed on the end of the wire. However, the press may also be worked in the way that the wire is fed so as to protrude in front of the press dies, so that the material for the head of the nail will be left on the end of the wire. In this instance the finishing operation for giving the head its desired form can be effected while the blank is held between the dies of the four die press and part of the mould necessary for this operation may be formed by the dies themselves.

The improvements forming the subject matter of this invention relates to a machine operated in this manner and the invention has for its object to create a process by which nails may be formed having heads of a perfect form, and a machine of a cheap and simple construction and operation.

In the following the invention will be described reference being had to the annexed drawings, in which

Fig. 1 is an elevation partly in section of the vital part of a horseshoe nail machine, the drawing being a diagram showing the parts in the moment the press dies are to make the first pressing movement.

Figs. 2-8 are diagrams showing the press dies and the iron rod in their consecutive positions during the forming of a nail blank. Fig. 9 shows only for matter of illustration a suitable form of a four die press, looking in the direction of the wire fed in between the dies.

The wire or rod *a*, on the end of which the nail blank is to be formed by means of the four radially disposed dies, of which two, *b* and *b'* are shown in section in Fig. 1, is held by a feeding arm *e*, which can be oscillated on the pivot *v* to and fro by means of a cam *h*, acting against a roller *e'*, a spring *g* pressing the arm against the said cam. In the said arm a gripper *f* actuated from a cam *i* through the lever *k*, the rod *l*, the lever *p*, and a spring *q*, serves to hold the wire and at intervals to leave it loose

so that the lever may move opposite the direction of the arrow *x* to take hold of material for a new nail.

After the first pressing operation (Fig. 2) the feeding lever will take the wire so that the head of the nail will have the position shown in Fig. 3, whereupon the second pressing takes place (Fig. 4).

During this first and second pressing, the spring *g*, which is a very strong spring, has the effect to exert a strong pulling action on the wire as indicated by the arrows *y*, partly for the purpose of shortening the length of the pyramid *m'*, partly for the purpose to positively prevent the slipping of the corners *c'* of the dies on the pyramid in the second press operation.

In the position of parts Fig. 4, when the shank has the form *n*² and the head the form *m*² a suitable tool comes in action and gives the head its proper form, the sloping surfaces *w* of the dies serving as a mould for the part of the head, uniting the same with the shank.

However this riveting operation, which in itself forms no part of the invention may also, as in other known machines, be effected after the nail blank has been severed from the wire end.

The next to be done is now to press the pyramid *o* on the point end of the nail, and this may be done by a third—preferably by a third and a fourth pressing operation as illustrated in the Figures 5, 6 and 7. By these press operations the sharp corners *c*² of the dies grip into the material and as the operative faces of the dies are diverging from this corner, and the cam *h* is capable of exerting a certain resistance, the pressing out of this pyramid so as to form the point of the nail blank very close to the crown of the head will be easily effected.

The wire is now brought to the position Fig. 8 and the nail blank may be severed by a blow of a hammer or by a cutting tool in well known manner. The wire now has its original position (shown in Fig. 1) and the pressing of a new nail commences.

What I claim is:

1. In the manufacture of horse shoe nails by means of a four die press, the process comprising first compressing a tapered head blank on the end of a wire, thereupon clamping the so-formed blank a second time between the dies at points remote from the point

of least taper and pressing the head a second time while exerting a stretching action on the wire, whereby excessive displacement of the metal incident to the pressing, in the direction of the head blank, is inhibited, and compressing the head blank thereafter while it remains between the dies to cause it to fill a head shaped recess in said dies.

2. In the manufacture of horse shoe nails by means of a four die press, the process comprising first compressing a tapered head blank on the end of a wire, thereupon clamping the so-formed blank a second time between the dies at points remote from the point of least taper and pressing the head a second

time while exerting a stretching action on the wire, whereby excessive displacement of the metal incident to the pressing, in the direction of the head blank, is inhibited, and compressing the head blank thereafter while it remains between the dies to cause it to fill a head shaped recess in said dies, advancing the wire between the dies to bring a new portion of wire adjacent the point of the nail between said dies, and pressing said new portion to form the point of the nail.

In testimony whereof I have signed my name unto this specification.

ADOLF MOELLER.
